UNITED STATES PATENT OFFICE.

FREDERICK K. MAERZ, OF CLEVELAND, OHIO, ASSIGNOR TO THE SCOTT-ULLMAN CO.,
OF CLEVELAND, OHIO, A CORPORATION OF OHIO.

DESIGN FOR A BODY-PLATE FOR LIGHTING-FIXTURES.

53,009.

Specification for Design.

Patented Feb. 18, 1919.

Application filed October 29, 1917. Serial No. 199,187. Term of patent 3½ years.

To all whom it may concern:

Be it known that I, FREDERICK K. MAERZ, a citizen of the United States, residing at Cleveland, in the county of Cuyahoga and State of Ohio, have invented a new, original, and ornamental Design for a Body-Plate for Lighting-Fixtures, of which the following is a specification, reference being had to the accompanying drawing, forming part thereof.

Figure 1 is a perspective view of a body plate for lighting fixtures, showing my new design.

Fig. 2 is a bottom view of the same.

I claim:

The ornamental design for a body plate for lighting fixtures, as shown.

FREDERICK K. MAERZ.
